UNITED STATES PATENT OFFICE

2,024,785

CONTINUOUS-FORM SHIPPING AND
ACCOUNTING DEVICEHarry C. Tobey, Chicago, Ill., assignor to United
Autographic Register Co., a corporation of Illi-
nois

Application October 13, 1932, Serial No. 637,627

3 Claims. (Cl. 282—12)

This invention relates particularly to means for facilitating shipments and accountings pertaining thereto. The device is well adapted, for example, to the purpose of express shipments, whether sent C. O. D. or otherwise.

5 The primary object is to provide a continuous-form multi-copy device adapted for the use of shippers which may be filled out in the office of the shipper, each set of forms providing all the 10 record-slips, or record-coupons, needful for the record-files of the shipper and the express company, or carrier.

In the improved device, provision is made for attaching to the package to be shipped a delivery 15 sheet which is to be signed and given as a receipt to the express company by the consignee; a way-bill which ultimately is forwarded to an auditor of express receipts for accounting purposes (distribution of revenue to carriers); and a way-bill 20 label which remains on the package, but is available for identification of the package in the event that the other slips or coupons become injured or detached during transit.

The improved device preferably comprises at 25 least four strips of continuous forms, the forms being arranged in sets and detachably connected together at their ends. The slips and/or coupons of each set are given an identifying character or number which may be printed thereon at the 30 time of the printing of the forms. The sets of forms may be numbered serially, and this number may serve as the shipper's identifying number for the shipment to which the particular set was applied. The forms may also be provided 35 with blanks for receiving the customer's order number and the shipper's factory order number.

40 Preferably, the two intermediate strips are detachably connected together at one lateral edge, thus forming a dual strip; and this dual strip comprises the delivery sheet, the way-bill, and the way-bill label. The slip of which the delivery sheet forms a coupon also has another coupon which may be utilized as a shipping label, or as a 45 shipment-data coupon containing detailed data of the shipment, as desired.

When it is desired to make a shipment, the shipper may cause a set of the forms to be filled out, employing for the purpose an autographic register, a typewriting machine, or a duplicating 50 machine of any suitable character.

The invention is illustrated in a preferred embodiment in the accompanying drawings in which:

55 Fig. 1 is a broken perspective view of an autographic register loaded with a zig-zag folded

packet of continuous-form stationery embodying the invention; Fig. 2, a broken perspective view showing a portion of the continuous-form stationery; Fig. 3, a front face view of the front or upper form of a set as preferably arranged, this 5 slip constituting a shipper's receipt; Fig. 4, a reverse face view of the slip shown in Fig. 2, the terms and conditions of agreement between the express company and the shipper appearing thereon; Fig. 5, a developed (open) view of a dual 10 slip which, according to the preferred arrangement, constitutes the two intermediate slips of a set, embodying a delivery sheet (coupon), a way-bill, a way-bill label, and an additional coupon which, in Fig. 3, appears as a shipping label; Fig. 15 15 6, a reverse-side view of the dual form shown in Fig. 5; Fig. 7, a front face view showing a combined forwarding-office coupon and destination district accounting office coupon (abstract advice), which constitutes the fourth slip of the set, 20 according to the preferred arrangement; Fig. 8, a view illustrating the manner in which the delivery sheet, the way-bill, and the way-bill label are folded (after first detaching the shipping label) to enable the folded parts to be attached 25 to the package, the reverse-side of the way-bill label appearing in Fig. 8; Fig. 9, a front view of the folded device shown in Fig. 8, this view showing the reverse side of the way-bill which is adapted to contain routing information, or the like, to 30 be filled in by agents of the express company; Fig. 10, a view of the folded device after the delivery sheet (coupon) and the way-bill (coupon) have been detached at the destination, it being understood that the way-bill label and the past- 35 40 strips employed for securing the delivery sheet of the way-bill to the package remain pasted upon the package after detachment of the delivery sheet and way-bill; Fig. 11, a view illustrating the delivery sheet and the way-bill (coupons) after detachment thereof from the package; Fig. 12, a broken view illustrating the manner in which the shipping label and the combined delivery sheet, way-bill, and way-bill label may be attached to a package; and Fig. 13, a plan view 45 of a shipment-data coupon which may be employed in the continuous-form stationery as a substitute for the shipping label, in which case the package may be addressed in any desired manner, and the shipment-data coupon may be 50 retained by the shipper, or may be forwarded to the consignee, according to the pleasure of the shipper.

Describing the preferred construction illustrated, I designate slip one of a set of forms, 55

constituting a shipper's receipt, this slip having printed on its back the terms and conditions of the agreement upon which the shipment is made; II designates a dual slip, which comprises the two intermediate slips of the set, one slip comprising the shipping-label and the delivery-sheet and the other slip comprising the way-bill label and the way-bill; and III designates the fourth slip of the set, which comprises the forwarding-office coupon and the destination district accounting office coupon.

Referring to Fig. 1, R designates a small portable autographic register which may be employed as a simple means for enabling a set of forms to be filled in, and P designates a packet of zig-zag folded stationery embodying the invention, the strips of stationery being folded in such manner that the various slips of each set are in superposed relation. Fig. 2 shows a fragment of the continuous-form stationery previous to the zig-zag folding of the stationery to form a packet, it being understood that the folding occurs along the line of weakening between the sets of forms.

Describing the improved shipping and accounting device more in detail, the first sheet of the set of forms is designated A. The front face of this sheet is provided with blanks for the name and address of the consignee, indicated at the points 1; a blank for the customer's order number, indicated at 2; a blank for the shipper's factory order number, indicated at 3; a serial number for the set of forms, indicated at 4 as the number 1446; the name of the shipper, indicated at 5; blanks for the signatures of the shipper's representative and the express company representative, indicated at 6 and 7 respectively; and a title for the sheet indicated at 8 as "Shipper's receipt".

The face of the slip A also contains suitable blanks for receiving data, such as the "Declared value" of the shipment, the weight of the shipment, etc.

Upon the reverse side of the slip A are printed the usual terms and conditions upon which the shipment is made, as partially indicated at 9.

Referring to Figs. 5 and 6, the dual-slip device II comprises a slip B and a slip C which are detachably connected at one lateral edge at the perforate line 10. In practice, the dual-slip is folded so that the slip C will lie back of the slip B. The slip B is shown as comprising a shipping-label B', a delivery sheet (consignee's receipt to express company) B², and a pasting strip B³. The coupons B' and B² are detachably connected at the transverse perforate line 11; and the pasting strip is detachably connected with the coupon B² at the perforate line 12. The strip B³ preferably is provided with perforations 13 for a purpose which will be explained later.

The coupons of the slip B are, in general, provided with blanks which correspond with the blanks on the shipper's receipt A, and, in practice, a carbon sheet is interposed between the slip A and the slip B, so that data filled in the blanks on slip A will be reproduced upon the coupons B' and B². The coupon B² is provided with a consignee's signature blank as indicated at 14.

As appears from Fig. 6, the reverse side of the coupon B' is left blank, and has printed thereon notice that this surface is to be used as a pasting surface by means of which the shipping-label may be attached to the package.

The reverse side of the delivery-sheet or coupon B² preferably is provided with a carbonized surface as indicated at 15. This serves as a

transfer medium whereby the way-bill C² is filled out at the time when the shipper's receipt A is filled out in the office of the shipper. It would be possible to employ a transverse slip of carbon paper at this point, but the carbonized surface is simpler.

The front surface of the way-bill label C' is provided with blanks, as indicated at 16, wherein the routing may be stamped by an express agent in case the way-bill becomes detached.

The reverse side of the way-bill C² is provided with blanks wherein routings may be stamped by an express company agent, these blanks being indicated at 17. It will be understood that this surface of the way-bill is not filled in at the office of the shipper.

The slip or sheet III which constitutes the fourth slip of the set is designated D. It comprises, as shown in Fig. 7, a forwarding office coupon D' and a destination district accounting office coupon (Abstract advice) D² connected by a line of weakening 18. In practice, a carbon sheet may be interposed between the rear surface of the slip C and the front surface of the slip D so that the necessary data will be filled in by transfer when slip A is filled in at the office of the shipper. The slip D' preferably is provided with a printed description indicating that this coupon is to be retained by the forwarding office of the express company. Thus, at the point 18a appears the legend "Forwardly office coupon". Also, the coupon D² preferably is provided with means to indicate that this coupon is to be forwarded to the destination district accounting office. Thus, at the point 19 is the legend "Des- 35 tination district accounting office coupon".

Assuming a set of forms to have been properly filled in at the office of the shipper, the necessary data pertaining to the particular shipment having been written or printed in the appropriate blanks, the shipment is received by the express company and an agent of the express company signs the shipper's receipt at the blank designated 7, this slip being then given to the shipper.

If desired, before the shipment is taken to the express office, the shipper may detach the coupon B' (the shipping label) and paste this label upon the package; or this may be left for the express company to attend to.

The delivery sheet or coupon B² and the underlying way-bill coupon C² are then folded upwardly over the face of the way-bill label C', it being noted that the coupons C' and C² are detachably connected together at the perforate line 20. The coupons are so proportioned that the attaching strips B³ and C³ project beyond the upper edge of the way-bill label, it being noted that the coupon B² lies between the coupon C² and the face side of the way-bill label. An adhesive is then applied to the rear face of the coupon C' and perforate attaching-strip B³. Some of the adhesive will pass through the perforations, so that the attaching-strip C³ will be secured to the attaching-strip B³ and the latter will be secured to the package. Thus, the way-bill label may be firmly glued to the package, and the attaching-strips projecting above the upper edge of the way-bill label may be firmly glued to the package. In this condition, the delivery sheet B² is housed between the way-bill C² and the way-bill label, the latter two elements remaining connected together along the perforate line 20.

When the package reaches its destination, the delivery-sheet and way-bill may be readily detached by tearing first along the perforate line 75

20 and then along the coincident perforate lines 12 and 21, the latter being the line of connection between the coupon C² and the attaching strip C³.

5 The agent of the express company at the delivery station obtains the signature of the consignee on the coupon B². The coupon B² is then forwarded to the district accounting bureau in charge of the destination office; the way-bill is passed on to the auditor of express receipts, to enable proper distribution of revenue to the carriers to be effected; and the way-bill label remains on the package.

10 Referring to Fig. 13, the coupon B' may be used in the improved device in lieu of the shipping label, in which event the package may be addressed to the destination office in any desired manner. The coupon B' is provided with suitable blanks for receiving the name of the consignee, the customer's order number, the shipper's factory order number, and is provided with additional data blanks, as indicated at 22. Thus, this coupon may be employed by the shipper for receiving detailed data concerning the particular shipment.

15 25 The improved device enables all the various coupons desirable for effecting and keeping a proper record of shipments of this nature and enabling proper accountings to be made as between the express company and the shipper and 30 as between the express company and the various carriers over whose lines the shipment is made, enables these coupons to be filled out in an orderly manner in the office of the shipper, thus obviating the danger of errors, avoiding loss of slips, 35 etc. Numerous grave objections to devices which have long been in use for effecting shipments of this character are overcome by the present invention. It is unnecessary to enumerate the many objections which exist with respect to devices previously in use. Not only are the more common objections of serious character overcome by the improved device, but a vast amount of wastage of shipping forms is obviated, also.

40 Those skilled in the art will readily understand 45 that the provision of continuous-form stationery having all of the necessary coupons for record and accounting purposes required by shipper and express company enables the forms to be filled in on a suitable machine with precision and high 50 legibility, thus obviating troublesome and expensive errors.

45 The foregoing detailed description has been given for clearness of understanding only, and no unnecessary limitations should be understood 55 therefrom, but the appended claims should be construed as broadly as permissible in view of the prior art. Additional copy strips may be employed, if desired; the order of the strips may be changed without departure from the invention; and some variation in the constitution and arrangement of the various coupons may be desirable for certain purposes. Preferably the slips B and C are detachably united at one edge; and, preferably, slips A and D are wholly separate from 60 slips B and C. However, a different arrangement may be adopted, if desired. The folding of the duplicating strips in zig-zag manner to form a packet enables the continuous-form stationery to be kept in neat packages and placed in a suitable 65 machine for use. The lines of folding are at the perforate lines where the forms are connected together at their ends.

Referring to Fig. 1, 22 designates a carbon-sheet between the slips A and B; and 23 designates a carbon-sheet between the slips C and D.

70 Referring to Fig. 3, the blanks designated 24 bear an inscription to prevent marking thereat. Corresponding spaces are thus left free at 24^a (Fig. 5), at 24^b (Fig. 6), and at 24^c (Fig. 7) for the use of the express agency.

Also, as appears from Fig. 6, no transfer medium is applied to the back of the shipping-label 10 B', so that the blanks 16 of the way-bill label C' (Figs. 6 and 10) will be available to the express agency, if needed, as by loss of way-bill and delivery-sheet.

75 Referring to Fig. 9, the back of the way-bill 15 coupon C² is provided with blanks 25 which are available to the express agency for the stamping of routings. This side of the way-bill is exposed to view during shipment.

20 The serial (form) number 1446 appears (printed) on all coupons, including the shipping-label, the way-bill label, and the shipment-data label (when employed).

25 What I regard as new, and desire to secure by Letters Patent, is:

1. Continuous-form stationery adapted for use in a duplicating machine, comprising a series of similar sets of forms connected end-to-end, each set having an upper slip and an underlying registering slip connected with each other at one lateral edge by a line of folding, each of said slips being similarly divided into two adjacent parts by a transverse fold line and each of said slips being provided at one end with a transverse strip connected thereto by a line of weakening, said strips being in register and one having cut-out portions to admit glue to the companion strip.

2. Continuous-form stationery, adapted for use in a duplicating machine, comprising a series of similar sets of forms connected end-to-end, each set having an upper slip and an underlying registering slip connected with each other at one lateral edge by a line of weakening, each of said slips being divided by registering transverse lines of weakening into two adjacent and substantially equal parts and a smaller third part, the equal parts being adapted to be folded together along their connecting transverse lines of weakening into registration and the third part of one of said slips having cut-out portions whereby glue may be applied to one of the equal parts and to both of the third parts simultaneously.

3. A packet of zig-zag folded continuous-form stationery, adapted for use in a duplicating machine, comprising: a series of similar sets of forms connected end-to-end, each set having an upper slip and an underlying registering slip connected with each other at one lateral edge by a line of weakening, each of said slips being divided by registering transverse lines of weakening into an upper part, an adjacent lower part of substantially equal size, and a smaller bottom part, the upper parts of both slips having register perforations and adapted to be folded along their connecting transverse lines of weakening into registration with the lower parts, and the bottom part of the upper slip having cut-out portions whereby glue may be applied to the back of the upper part of the underlying slip and to both of said bottom parts simultaneously.

HARRY C. TOBEY.
